(57) **CLAIM**

The ornamental design for an anvil plate for use with an impact bullet puller, as shown and described.

DESCRIPTION

FIG. 1 is a top perspective view of the anvil plate for use with an impact bullet puller;

FIG. 2 is a bottom perspective view of the anvil plate for use with an impact bullet puller;

FIG. 3 is bottom plan view of the anvil plate for use with an impact bullet puller;

FIG. 4 is a top plan view of the anvil plate for use with an impact bullet puller;

FIG. 5 is a side elevation view of the anvil plate for use with an impact bullet puller; and,

FIG. 6 is a top perspective view of the anvil plate for use with an impact bullet puller on a reloading press.

The broken lines shown in the drawings are for the purpose of illustrating portions of the article that form no part of the claimed design.
